(57) **CLAIM**

The ornamental design for a dog pack, as shown and described.

DESCRIPTION

FIG. 1 is a right end perspective view of a dog pack which embodies the present design in full lines, the items shown in broken lines reflect objects placed inside of the dog pack as well as a dog upon which the dog pack is mounted and such items shown in broken lines are depicted for illustrative purposes only and form no part of the claimed design; FIG. 2 is a left end perspective view thereof; FIG. 3 is a top plan view thereof; FIG. 4 is a bottom plan view thereof; FIG. 5 is a front elevational view thereof; FIG. 6 is a rear elevational view thereof; FIG. 7 is a right side elevational view thereof; and, FIG. 8 is a left side elevational view thereof.

The broken lines also shown in FIGS. 2, 3, 5, 6, 7 and 8 are for illustrative purposes only and form no part of the claimed design.

It is understood that the discontinuous strap shown in FIGS. 3, 4, 5 and 6 indicates that said strap is of indeterminate length.
